UNITED STATES PATENT OFFICE.

ANDERSON MANSFIELD HOLMES, OF BALTIMORE, MARYLAND, ASSIGNOR, BY DIRECT AND MESNE ASSIGNMENTS, OF FIFTEEN ONE-HUNDREDTHS TO MARIE SMITH, FIFTEEN ONE-HUNDREDTHS TO ANNIE L. FISK, NINETEEN ONE-HUNDREDTHS TO OSCAR I. WOODLEY, EIGHTEEN ONE-HUNDREDTHS TO WILLIAM F. METCALF, AND THIRTY-THREE ONE-HUNDREDTHS TO EDWARD L. TORSCH.

ATOMIZER.

1,351,012.

Specification of Letters Patent. Patented Aug. 24, 1920.

Application filed August 27, 1919. Serial No. 320,109.

To all whom it may concern:

Be it known that I, ANDERSON MANSFIELD HOLMES, a citizen of the United States, residing at Baltimore, in the State of Maryland, have invented certain new and useful Improvements in Atomizers, of which the following is a specification.

This invention relates to improvements in atomizers, and has for its object to provide 10 a simple and convenient apparatus so constructed and arranged that the medicine to be inhaled by the patient will be discharged therefrom in the form of a cool relatively dry vapor.

15 The invention consists of the novel construction and arrangement of the parts and combination of parts hereinafter more fully set forth in the following specification and pointed out in detail in the appended claims.

20 In the accompanying drawing,—

Figure 1 is a side elevation of a structure embodying my invention.

Fig. 2 is a vertical longitudinal section of Fig. 1 through its medial plane.

25 Fig. 3 is a top plan view of the water reservoir.

Fig. 4 is a vertical section on the line 1—1 of Fig. 2.

Fig. 5 is a top plan view of Fig. 1.

30 Referring to the accompanying drawings, forming part of this specification, and in which like reference numerals designate like parts throughout the several views thereof, 1 designates a casing of metal, or other suitable material, and having a water reservoir 2 for supplying water to the boiler 3; the said reservoir 2 being provided with a pipe 4 in the top thereof through which the reservoir is filled, and extending outside the casing 1 near the top thereof and having a stop cock 5 to open or close communication with said reservoir 2. The said reservoir 2 is also provided as best seen in Fig. 4, with a water pipe 6 which extends down to the bottom of the said tank and an air pipe 7 which projects through the top of said tank. The pipes 6 and 7 project up through the top of the casing 1, are provided, the pipe 6 with a valve 8 and the pipe 7 with a valve 9, and are joined by a union 10 from which latter the pipe 11 leads to the boiler 3. The boiler 3 is also connected with the condensing chamber 12 by the pipe 30 through which the steam from the boiler 3 passes to the condensing chamber 12, which connects with a second condensing chamber 13 by a pipe 14 which has one end open near the top of the chamber 12 and the other end extending down close to the bottom of the chamber 13. The said condensing chamber 13 is provided with an outlet pipe 15 near the top thereof and having a discharge nozzle 16 on its outer end, which causes the vapor to be discharged in the form of a spray and also causes a pressure in the condensing chambers 12 and 13. The said condensing chamber 13 is provided with excelsior, or other suitable material, which holds in its pores and upon its surface the medicine that is supplied to said chamber 13 through the pipe 17 at the top thereof, thereby preventing the medicine from dropping down into the water of condensation at the bottom of the chamber 13 and also permitting a more perfect absorption of the medicine by the steam as it passes up through said excelsior. The condensing chamber 12 is provided with a discharge pipe 18 which has its lower end terminating near the bottom of the chamber 12 and its upper end projecting through the casing 1 near the top thereof and provided with a valve 19 to open and close said pipe. The water of condensation in chamber 12 is discharged through said pipe 18 at any time while the apparatus is in operation by simply opening the valve 19 as there is a steam pressure within the apparatus sufficient to cause said discharge owing to the smallness of the discharge nozzle 16. The water of condensation that collects in the chamber 13 will be drawn into chamber 12 through the pipe 14 whenever the heater 20 is removed or its flame is extinguished, as a vacuum will be created in said chamber 12, which causes a suction through said pipe 14. The tank 2 is filled through the pipe 4 by the use of the funnel 21 which is adjustable on the rod 22 and is adapted to be swung about the axis of said rod so that it will align with the upper end of the pipe 4. The boiler 3 is held by an arm 23 which latter is adjustable on the rod 24. The water is supplied to the boiler 3 from the tank 2 by forcing air through the pipe 4 to said tank 2 which causes the water to flow up through

the pipe 6 and through the pipe 11 to the boiler 3. If it be desired to force air into said boiler 3 to create a pressure therein, the valve 8 is closed and valve 9 opened which 5 allows air to pass from the tank 2 through the pipe 7 union 10 and pipe 11 to the boiler 3. Between the condensing chambers 12 and 13 is a gasoline chamber 25 provided with a pipe 26 which projects through the side of 10 the casing 1 and has its inner end terminating just below the top of said gasoline chamber and a pipe 27 which has its lower end projecting down to near the bottom of the gasoline chamber 25 and also projects 15 through the side of the casing 1. Said pipes 26 and 27 are provided respectively with valves 28 and 29 and are connected by a union 31 to the pipe 32 which latter leads to the heater 20. The gasoline is supplied to 20 the chamber 25 through the pipe 33. When it is desired to fill the heater 20 from the tank 25 the valve 29 is opened and air is forced through pipe 33 by a rubber bulb or other suitable device to the tank 25 and the 25 pressure therein will cause the gasoline to flow through the pipe 27 and pipe 32 to the heater 20. When it is desired to cause a pressure in the heater 20, valve 29 is closed and valve 28 opened and air is then forced 30 through the pipe 33 to the chamber 25 from which it passes through the pipe 26 and pipe 32 to the heater 20. The valve 28 is a three-way valve so that the air in the chamber 25 can be discharged through the valve 28 to 35 the atmosphere when desired.

It will be seen from the foregoing that as the steam generated in the boiler passes through the apparatus and expands therein, its temperature is reduced and much of its 40 moisture is precipitated so that it enters chamber 13 in a relatively dry condition. As it finally passes through the chamber 13 it takes up more or less of the medicament held by the excelsior or other body, and issuing 45 from the nozzle 16 under pressure, assumes the form of a fine spray or vapor. In

passing through the external air and to a distance of from two to three feet from the nozzle 16, it is further cooled, parts with most of its remaining water content, and 50 becomes a relatively dry medicated vapor of temperature lower than that of the surrounding atmosphere.

Having thus described my invention, what 55 I claim is:

1. An atomizer comprising a boiler, a condensing chamber having communication with said boiler, a pipe within said condensing chamber having one end terminating near the bottom and the other end projecting 60 through the wall of said condensing chamber near the top thereof, a second condensing chamber having communication with the first-named condensing chamber, and an outlet for said second condensing chamber and 65 having a nozzle secured thereto.

2. An atomizer comprising a boiler, a reservoir having communication with said boiler, a condensing chamber having communication with said boiler, a pipe within 70 said condensing chamber having one end terminating near the bottom and the other end projecting through the wall of said condensing chamber at the top thereof, a second condensing chamber having communication 75 with the first-named condensing chamber and having an inlet and an outlet, and a nozzle connected to said outlet.

3. An atomizer comprising a boiler, a heater for said boiler, a condensing chamber 80 having communication with said boiler, a pipe within said chamber having one end terminating near the bottom and the other end projecting through the wall of said condensing chamber near the top thereof, a second condensing chamber having communication 85 with the first-named condensing chamber, and an outlet for said second condensing chamber and having a nozzle secured thereto.

In testimony whereof I affix my signature. 90

A. MANSFIELD HOLMES.
